(57) **CLAIM**

The ornamental design for an athletic shoe, as shown and described.

DESCRIPTION

FIG. 1 is a front perspective view of an athletic shoe, showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The even length broken lines shown in the drawings depict portions of the athletic shoe that forms no part of the claimed design. The dot-dash broken lines surrounding the inner areas of FIGS. 1, 3, and 6 denote the boundaries of the design and form no part of the claimed design.
